DESIGN FOR A LOCKING COVER

Charles H. Nehls, Detroit, Mich.

Application September 5, 1939, Serial No. 87,055

Term of patent 7 years

To all whom it may concern:

Be it known that I, Charles H. Nehls, a citizen of the United States and a resident of Detroit, in the county of Wayne and State of Michigan, have invented a new, original, and ornamental Design for a Locking Cover, of which the following is a specification, reference being had to the accompanying drawing, forming part thereof.

I claim:

The ornamental design for a locking cover, as shown.

CHARLES H. NEHLS.
